US0D1078159S

(12) **United States Design Patent** (10) **Patent No.:** **US D1,078,159 S**
(45) **Date of Patent:** **** Jun. 3, 2025**

(54) **HAIR DRYER NOZZLE**

(71) Applicant: **Dongguan Meisheng Intelligent Technology Co., Ltd**, Dongguan (CN)

(72) Inventor: **Junmin Jiang**, Dongguan (CN)

(73) Assignee: **Dongguan Meisheng Intelligent Technology Co., Ltd**, Dongguan (CN)

(**) Term: **15 Years**

(21) Appl. No.: **29/881,671**

(22) Filed: **Jan. 5, 2023**

(30) **Foreign Application Priority Data**

Nov. 25, 2022 (CN) 202230789058.4

(51) **LOC (15) Cl.** **28-03**

(57) **CLAIM**

The ornamental design for a hair dryer nozzle, as shown and described.

DESCRIPTION

FIG. 1 is a first perspective view of a hair dryer nozzle showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the hair dryer nozzle that form no part of the claimed design.

1 Claim, 8 Drawing Sheets
